Primary Examiner — Darlington Ly(74) *Attorney, Agent, or Firm* — Tucker Ellis LLP**CLAIM**

The ornamental design for a ripper for granulating machine, as shown and described.

DESCRIPTION

FIG. 1 is a top, front and left side perspective view of a ripper for granulating machine embodying our new design; FIG. 2 is a rear and right side perspective view thereof; FIG. 3 is top and rear perspective view thereof; FIG. 4 is a front elevation view thereof; FIG. 5 is a rear elevation view thereof; FIG. 6 is a left side elevation view thereof, of which the right side elevation view is a mirror image; and, FIG. 7 is a top plan view thereof, of which the bottom plan view is a mirror image. The broken lines in the drawings illustrate portions of the ripper for granulating machine that form no part of the claimed design.
